CLAIM

The ornamental design for a golf club hosel sleeve, as shown and described.

DESCRIPTION

FIG. 1 is a side elevational view of our new design of a golf club hosel sleeve, the broken line showing of a golf club head is for illustrative purposes only and forms no part of the claimed design;

FIG. 2 is an enlarged perspective view of the golf club hosel sleeve;

FIG. 3 is a side elevational view of FIG. 2 thereof, the opposite side being a mirror image thereof;

FIG. 4 is a top end elevational view of FIG. 2 thereof; and,

FIG. 5 is a bottom plan elevational view of FIG. 2 thereof.
